UNITED STATES PATENT OFFICE.

ELIJAH A. OVENSHIRE, OF LOS ANGELES, CALIFORNIA.

DESIGN FOR AN INFORMATION AND DIRECTORY CABINET.

No. 39,649.

Specification for Design.

Patented Oct. 27, 1908.

Application filed July 1, 1908. Serial No. 441,510. Term of patent 7 years.

To all whom it may concern:

Be it known that I, ELIJAH A. OVENSHIRE, a citizen of the United States, residing at Los Angeles, in the county of Los Angeles and State of California, have invented a new, original, and ornamental Design for Information and Directory Cabinets, of which the following is a specification, reference being had to the accompanying drawing, forming part thereof.

The figure is a front elevation of an information and directory cabinet showing my new design.

The design consists of an elongated vertical box with a central panel in its front face

and rectangular boards at each side of said box each formed with a plurality of vertical panels, and below the elongated box is a cubical box with a sloping top, a horizontal panel being on each side of the lower box and a single horizontal panel surmounting the elongated box and side boards.

I claim:

The ornamental design for an information and directory cabinet, as shown and described.

ELIJAH A. OVENSHIRE.
